UNITED STATES PATENT OFFICE

FRED M. OPITZ, OF MILWAUKEE, WISCONSIN

DESIGN FOR AN AIR CONDITIONING DEVICE

Application filed September 18, 1931. Serial No. 41,143. Term of patent 3½ years.

To all whom it may concern:

Be it known that I, FRED M. OPITZ, a citizen of the United States, residing at Milwaukee, in the county of Milwaukee and State of Wisconsin, have invented a new, original, and ornamental Design for Air Conditioning Device, of which the following is a specification, reference being had to the accompanying drawings, forming part thereof.

Figures 1 and 2 are, respectively, front and rear perspective views showing my new design.

I claim:—

The ornamental design for an air conditioning device, as shown.

In witness whereof, I hereunto subscribe my name this 10th day of September, 1931.

FRED M. OPITZ.
